(57) **CLAIM**

The ornamental design for an eye-tracking module, as shown and described.

DESCRIPTION

FIG. 1 is a perspective view of an eye-tracking module that can be assembled with a head-mounted display (HMD) device;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof; and,

FIG. 8 is another perspective view thereof.

The broken lines in the drawings depict portions of the eye-tracking module that form no part of the claim.
